UNITED STATES PATENT OFFICE.

JAMES H. RHODES, OF CHICAGO, ILLINOIS.

DESIGN FOR A SPRINKLER.

SPECIFICATION forming part of Design No. 31,485, dated September 5, 1899.

Application filed June 30, 1899. Serial No. 722,477. Term of patent 31 years.

To all whom it may concern:

Be it known that I, JAMES H. RHODES, a citizen of the United States, residing at Chicago, in the county of Cook and State of Illinois, have invented and produced a new and original Design for a Sprinkler for Disinfectant and other Like Bottles, of which the following, in connection with the accompanying drawings, is a full, clear, and exact specification.

In the said drawings, Figure 1 is a perspective view of a sprinkler for disinfectant-bottles embodying my design, and Fig. 2 is a perspective view looking upward under the cap. The leading features of my design consist of the cap A and the rose B rising therefrom. The cap A is cylindrical in plan view and hollow underneath, as shown in Fig. 2, and its exterior and interior are spirally ribbed on the sides, as shown at a. The rose B is upwardly flaring and has a reduced neck b ris-

ing from the top of the cap A. Depending from the under side of the cap A is a tube C, having its lower end bent or deflected to one side, as shown at c. On the upper side of cap A and slightly to one side of the center thereof is an upwardly-extending gooseneck D, and on the upper end of the gooseneck is a knob-like portion d. To one side of the gooseneck D, upon the surface of the cap A, is located a vertical protuberance E, having its upper end provided with perforations e.

Having thus described my invention, what I claim as new therein, and desire to secure by Letters Patent, is—

The design for a sprinkler for disinfectant and other like bottles, substantially as herein shown and described.

JAMES H. RHODES.
